PUSH OR PULL TOY

Leslie Perhacs, Jr., Topanga, Calif., assignor to Cragstan
Industries, Inc., New York, N.Y., a corporation of New
York

Filed Mar. 12, 1969, Ser. No. 16,190

Term of patent 14 years

Int. Cl. D21—02

U.S. Cl. D34—15

FIG. 1

Des. 217,176

PAGE 2

FIG. 2

FIG. 3

FIG. 4

FIG. 5

FIG. 1 is a perspective view of my new design, for a push or pull toy;

FIG. 2 is a top plan view thereof;

FIG. 3 is a side elevational view, the opposite side being substantially a mirror image thereof;

FIG. 4 is a rear elevational view thereof; and

FIG. 5 is a bottom plan view thereof.

The conventional cylindrical guide stick is shown fragmentarily for convenience of illustration.

I claim:

The ornamental design for a push or pull toy, substantially as shown and described.
